CIGARETTE EJECTOR

George Breitwieser, Flushing, N. Y.

Application February 23, 1939, Serial No. 257,837

7 Claims. (Cl. 312—78)

This invention relates to cigarette ejectors, and has for its object to provide such an ejector which may be readily filled, and from which the cigarettes may be ejected one by one.

For this purpose, the invention consists of a cylindrical casing having the cigarettes disposed therein in a circular row, with a spacer passing the cigarettes, so that the end cigarette may be pushed upon a piston which is vertically movable and the cigarette discharged from an opening in the cover of the casing.

The invention comprises means to move the cigarette to the piston; means to move a cigarette vertically out of the casing; means to return the parts to initial position, and means to lock the parts when all cigarettes have been discharged, separately and in combination.

The invention will be described hereinafter, embodiments thereof shown in the drawing, and the invention will be finally pointed out in the claims.

In the accompanying drawing:

Figure 1 is a vertical central section taken on line 1—1 of Figure 2;

Figure 2 is a horizontal section on line 2—2 of Figure 1;

Figure 3 is a vertical section on line 3—3 of Figure 1;

Figure 4 is a partial sectional view like Figure 2, but showing the ejector in non-operative position after all cigarettes have been used up, taken on the line 4—4 of Figure 1;

Figure 5 is a perspective view of the piston enclosing member;

Figure 6 is a perspective view of the piston member; and

Figure 7 is a sectional view of a modified form of piston moving means.

Similar characters of reference indicate corresponding parts throughout the various views.

Referring to the drawing, and more particularly to Figure 1, the ejector has a cylindrical shape, with a cover having a central operating button at the top thereof, and an opening for the ejection of single cigarettes. The ejector may be filled by removing the cover, and after inserting the cigarettes again closing it.

The casing 10 has the cover 11 provided with a central opening 13 for the passage of the button 14. The cover 11 has a rim 15 to engage the top end of the casing. The cover 11 also has an opening 16 for the passage of a single cigarette when being ejected.

Within the casing 10, at its bottom, is a ridge

member 17 extending almost entirely around the bottom, leaving a gap for the cigarette ejecting mechanism and the piston. This ridge begins at 18 and ends at 19. Below the peak of this ridge is the actual bottom upon which rests an end 20 of the piston 21, with the laterally extending part 22. A cigarette moved from the ridge 17 can drop upon the part 22 and have its end rest thereon. The piston 21 has an upright 23, with a slot 24, and a bent over portion 25. Upon the bent over portion 25 a spring 26 is seated, the other end of which extends upwardly and presses against the wall 27. The action of the spring 26 is to press the piston downwardly, this being its normal position. A U-shaped enclosing member 30 has an elongated slot 31 therein and is secured to the casing 10 by rivets 32. One leg 33 of the U-shaped member 30 engages a slot 34 in the lower end of the piston 21, so as to permit the piston to be guided by the member 30, in vertical up and down direction. Secured to the member 30 by soldering or the like, is a pair of vertically spaced discs 36 and 37, held spaced by a tubular member 38 provided with collars 39 and upsets 40. A spring 41 is disposed between the lower surface of the upper disc 36, and a collar 42, which surrounds the tube 38, from which extends outwardly an arm 43 which supports the spacer 44 about the length of a cigarette and which is slightly curved to embrace a side of a cigarette. The spring 41 has the tendency to push the cigarette immediately in front of the spacer 44, in the direction of the arrow 45 in Figure 2, that is, towards the piston 21. When the casing is filled with cigarettes, the spacer 44 acts upon all of the cigarettes, pushing the one farthest away upon the piston 21. The cigarettes 46 rest on the ridge 17, and are guided in upright position circumferentially in the space between the casing and discs 36 and 37.

Within the tubular member 38, a rod 14^a secured to the button 14 is capable of being moved up and down, the button 14 having a collar 47 to limit the upward movement of the rod 14^a. To the tubular member 38 is secured a bracket 48 having a shaft 49 to which a lever 50 is pivoted. This lever 50 has a hook-shaped portion 51 entering through a slot 52 in the tube 38, and extending into the path of the rod 14^a. The lever 50 extends at the other side of its pivot, within the slot 24 of the piston 21. When the button is pressed downwardly, the rod 14^a pushes the portion 51 downwardly, which raises the end 53 upwardly, and hence the piston 21. A cigarette 55

pushed onto the part 20 is thereby raised upwardly and moved out of the opening 16 of the cover 11. When the button 14 has been released, the spring 26 returns the piston 21 to its normal 5 downward position, the lower 50 pushing the rod 14a with its button 14 upwards to normal position. After one cigarette has been ejected, the action of the spring 41 causes the next adjacent cigarette, through the pressure exerted by the 10 spacer 44, to move from the ridge 17 to the part 22 of the piston 21.

After all the cigarettes have been ejected, the spacer 44 is pressed against the member 30, and thereby takes a position above the part 20 and 15 locks the part in position, in that any downward pressure on the button 14 is blocked, since the piston 21 is not able to move upwardly by reason of the obstruction presented by the spacer 44.

In Figure 7 is shown a modified form of piston 20 moving means, in which the piston 21 is connected with a flexible wire 60, at one end thereof, there being a presser member 61 at the other end of the wire 60. The wire 60 is within a tubular casing 62 secured to the plate 36 and to 25 the plate 37, passing through both. The tubular member 62 has an indented part 63 to form a seat for the end of the spring 64, the other end of which abuts against the presser member 61. The tubular member is curved as shown by 30 65. When this member 61 is pressed against the action of the spring, the end of the rod 60 secured to the piston 21 moves the piston upwardly, and when pressure is released the spring returns the presser member to its original position.

35 The invention then provides means to act upon circularly arranged cigarettes pressed in the direction of a piston which is raised to eject one cigarette after the other, by pressure applied exterior of the casing upon a button operating a centrally disposed rod, connected by a lever with the cigarette holding piston, which is guided vertically so as to eject a cigarette vertically through an opening in registration with the cigarette supporting part of the piston. When the cigarettes 40 have all been ejected, a backing action prevents further movement of the parts, and this acts as a signal to refill the casing.

While I have illustrated and described the preferred form of construction for carrying my invention into effect, this is capable of variation 50 and modification without departing from the spirit of the invention. I, therefore, do not wish to be limited to the precise details of construction set forth, but desire to avail myself of such 55 variations, modifications and adaptations as come within the scope of the appended claims.

I claim:

1. In an article dispensing machine, a casing, 60 stop means in said casing, a support for the articles in said casing, said support terminating at one end adjacent said stop means and spaced from the latter approximately the width of an article, ejecting means movable in the space between said end of the support and said stop means, means for actuating said ejecting means, and yieldable follower means for urging the articles in sequence against said stop means, said follower means being so constructed and arranged with relation to said stop means that 65 when the follower means engages against said stop means as a result of the exhausting of the articles from the machine, said stop means will maintain said follower means overlapped with the ejecting means in the direction of ejection 70 to prevent actuation of said ejecting means. 75

2. In an article dispensing machine, a casing, guide means fixed in said casing and having a stop member, a support in the casing for the articles to be dispensed, said support terminating at one end adjacent said stop member, yieldable 5 follower means for urging the articles in succession along said guide means and against said stop member, an ejecting piston movable in said guide means and straddling said stop member with a portion on the support side of said stop member for receiving an article directly on said piston for ejection from said casing, and means for actuating said piston.

3. In an article dispensing machine, a casing, a hollow guide fixed to said casing and having a 15 stop wall, a support in the casing for articles to be vended having an end spaced from said stop wall, a yieldable follower adapted to urge said articles along the support across the space and against said stop wall, a piston lying normally in 20 the space between said stop wall and the adjacent end of said support for receiving an article forced against said stop wall, said piston having a portion lying within said hollow guide and connected with the piston across said stop wall, 25 means movable through said guide having connection to said piston for moving the latter to eject an article, and means for actuating said last-named means.

4. In an article dispensing machine, a casing, 30 a tubular guide fixed in said casing and having a foreshortened stop wall, a support in the casing for articles to be dispensed, said support terminating at one end adjacent said stop wall and spaced from the latter, follower means for yieldably urging the articles in succession against said stop wall, a piston having portions within and without said tubular guide and having a slot to receive said foreshortened stop wall, the portion of the piston outside said guide lying in the space between said stop wall and support and adapted to receive the articles from the support which are lodged against said stop wall, yieldable means in said guide urging said piston into initial inoperative position, means playing movably through 45 said guide and engaging said piston for throwing the latter in the act of ejecting the article against the influence of said yieldable means, and means for actuating said last named means.

5. In an article dispensing machine, a substantially cylindrical casing for containing articles to be dispensed arranged in a circular series, a guide fixed in said casing including a stop wall, yieldable means for urging the articles in succession against said stop wall, an ejecting plunger having parts thereof extending on both sides of said stop wall with one part thereof positioned to receive the article held against said stop wall, piston carrying means on the other side of the stop wall movable in said guide, a central actuating means mounted substantially centrally of the casing, a movable connection actuated by said actuating means and having a part playing through said guide and engaging the piston carrying means for operating the same on its ejecting movement, and yieldable means for returning and yieldably maintaining said piston in its initial position.

6. In an article dispensing machine, a casing for the articles to be dispensed, a guide secured in said casing and having a stop wall, a piston having parts extending on opposite sides of said wall and in part guided thereby, means for yieldably maintaining the piston in a low position for receiving articles, non-rotative discs secured 70 75

- to said guide and forming with the casing a curved chamber for the articles, a non-rotative tube connected between said discs, a follower member for engaging behind said articles having
- 5 a part rotatably mounted about said tube, actuating means movably mounted through said tube, and a lever carried by said tube having one end positioned to be engaged by said actuating means and the other end playing through said guide
- 10 for moving said piston.
7. In an article dispensing machine, a casing, guide means fixed in said casing and having a stop member, a support in the casing for the ar-
- ticles to be dispensed, said support terminating at one end adjacent said stop member, yieldable follower means for urging the articles in succession along said guide means and against said stop member, an ejecting piston movable in said 5 guide means and straddling said stop member with a portion on the support side of said stop member for receiving an article directly on said piston for ejection from said casing, and a U-shaped flexible wire connected at one end to said 10 ejecting piston for actuating the latter.
